Patented Mar. 6, 1917.
2 SHEETS—SHEET 2.

UNITED STATES PATENT OFFICE.

EDWARD F. HAMILL, OF CHICAGO, ILLINOIS.

SWITCHING DEVICE.

1,218,552.

Specification of Letters Patent.

Patented Mar. 6, 1917.

Application filed March 18, 1915. Serial No. 15,377.

To all whom it may concern:

Be it known that I, EDWARD F. HAMILL, a citizen of the United States, residing at Chicago, in the county of Cook and State of Illinois, have invented a certain new and useful Improvement in Switching Devices, of which the following is a full, clear, concise, and exact description, reference being had to the accompanying drawings, forming 10 a part of this specification.

My invention relates to switching devices and more particularly to that class of switching devices known as silent call wall switches for hospitals, although of course my invention is applicable to other uses.

When my invention is applied for hospital purposes it is designed to be controllable by a patient, for instance, in a manner to establish a signal which may call a nurse, which 20 signal must be established in several different places. A signal, for instance, must be given over the door of the room so that the nurse on the floor need not go back to the headquarters before responding, and in 25 many cases a pilot signal must be operated at some central point to indicate any group of substations from which a call might have originated.

One of the main objects of the invention 30 is to provide a switch of this character which will operate with the very least accompaniment of noise, thus not to disturb the patient. A further object of the invention is to provide switching mechanism which may 35 be of the wiping character to thus insure its positive actuation at all times.

It is of course essential in devices of this kind that the patient be called upon merely to actuate a push button in order to operate 40 the switching device. Thus an electromagnet is used to actuate the switching element, and my invention concerns itself particularly with the constructional features of this electromagnet and the particular manner of 45 operating devices interposed between the electromagnet and the switching element.

Furthermore my invention concerns itself with constructional features of the entire switching device, all as will presently appear 50 from the detailed description of one embodiment thereof set forth in the accompanying drawings in which—

Figure 1 is a front view of my improved device showing the push button together 55 with the attachment plug;

Fig. 2 is an enlarged side view of my im-

proved device with the cover plate in section;

Fig. 3 is a rear view of my improved device with the rear cover removed; 60

Fig. 4 is a longitudinal sectional view through the center of the device;

Fig. 5 is a sectional view on line *a—a* of Fig. 3;

Fig. 6 diagrammatically illustrates one 65 form of circuit connections for which my device is adapted, and

Figs. 7, 8 and 9 are fragmentary sectional views respectively on lines *c*, *b* and *d*.

My improved device includes a front 70 plate 1 preferably of metal having holes 2, 2 adapted to accommodate screws for attaching the front plate to the wall; rear-

wardly of this front plate an insulating block 3 is fastened through the agency of 75 the screws 4, metallic bushings 5 being interposed which are molded into the block 3.

A restoring button 6 projects from the front plate whose purpose will presently appear. Two jack thimbles 7, 7 project through the 80 front plate, being fastened to the block 3 by being riveted over contact springs 8. The jack thimbles 7 are surrounded by insulating bushings 9 so that these jack thimbles

are insulated from the plate 1. These jack 85 thimbles are adapted to coöperate with contact fingers 10, 10 mounted on the insulating block 11, thus forming a plug, a suitable flexible cord 12 being fastened to said

plug and having conductors extending re- 90 spectively into electrical contact with said fingers 10, 10. The cord terminates in a

push button device 13 having the push but- 95 ton 14 as well understood. The contact

fingers 10, 10 are split as shown, thus to 95 serve better the purpose of making contact with the jack thimbles 7. The insulating

block 3 also has internally screw threaded bushings 15 molded therein which are 100 adapted to receive screws 16 through the agency of which the cover plate 17 is held in place. This cover plate has a hole 18

which is adapted to fit over a screw 19 so 105 that the cover plate need be fastened only at its lower extremity (Fig. 2) by two

screws 16, the opposite end of the said cover having the hole 18 interlock with the screw 19, thus firmly securing the parts in position.

The screw 19 is desirably mounted upon an upwardly projecting arm 20 forming part of the heel piece 21 which mag-

netically unites the two cores of the solenoid 110

105

110

coils 22, 22. The solenoid cores terminate as shown more clearly in Figs. 2 and 4 in pole pieces 23 which are of the truncated pyramidal form. These particular pole pieces thus coöperate electromagnetically with great efficiency with the armature 24 of the entire electromagnet consisting of the two solenoids 22. This armature 24 has holes 25 through which the polar extensions 23 are adapted to pass. By virtue of the flaring form of these pole pieces the pivoted armature is maintained in association with these pole pieces with a practically constant air gap irrespective of the position of said armature. In order to support the armature I provide an arm 26 of non-magnetic material held in place on top of the solenoids through the agency of the locking ring 27, which rings are held in place by the polar extensions 23, the polar extensions preferably having screw threaded engagement with the core of their corresponding solenoids. The arm 26 has downwardly extending arms 27^a which carry the shaft 28, which shaft pivotally carries the bearing arm 29 riveted by means of the rivet 30 to the said armature 24. The rivet 30 also holds in position a flexible lift spring 31 which at its lower extremity (Fig. 4) is normally tending to move away from the corresponding extremity of the armature 24. The armature is designed to actuate a plunger 32, which plunger is rigidly fastened to a screw 33. The construction of this plunger will be more readily apparent from Fig. 4 where this plunger consists of an insulating sleeve 34 carrying a conducting ring 35, which conducting ring is locked in place by an insulating ring 36. A nut 37 is then provided upon the screw 33 having a coöperating washer and a second nut 38 with a coöperating washer also screw threadedly engaging the screw 33, in co-operation with the nut 37, fastens all of the parts thus enumerated securely together. The screw 33 is slidable within a bushing 39 so that the plunger may be moved to the right or left (Fig. 4) in accordance with the movements of the armature 24. The purpose of the spring 31 it may be pointed out is to permit the armature 24 to make a slight movement in response to the solenoids 22 whereby the armature attains a certain speed of movement before it is encumbered with the drag caused by moving the plunger 32. The spring 31 thus yieldingly serves to associate the plunger and the armature together, the spring 31 preventing the loud click which would otherwise happen if this spring were not pressed, and which in a hospital is undesirable.

Thus whenever the patient operates the push button, the armature 24 is attracted and the plunger 32 (Fig. 4) is moved from right to left. Now in order to restore this

plunger the restoring button 6 comes into play. This restoring button has a rod 40 slidably mounted in the block 3, which rod is encircled by a spring 41. This spring 41 normally pushes the restoring button and 70 rod to the left (Fig. 4). The rod 40 is of course of non-magnetic material, passes through the heel piece 21, and also finds a sliding bearing in the element 26.

It will thus be seen that should the armature 24 be in an attracted position, that in order to restore it to the position of Fig. 4, all that is necessary is to push in the restoring button 6 and the parts will again assume the position occupied in Fig. 4. The plunger 80 32 by reason of its conducting ring 35 controls the circuit through a plurality of switching springs. These switching springs respectively 42, 43, 44, 45, 46 and 47 are mounted upon an insulating block 3, 85 through the agency of screws as readily apparent.

These switching springs are in general of the shape most clearly shown at 45 in Fig. 4. Springs 43, 47, are considerably smaller 90 than the remaining switching springs as will be readily clear from the illustrations in Figs. 2 and 4. It will thus be seen that when the plunger 32 is in the position shown in Fig. 4, the conducting ring 35 closes circuit between springs 43 and 47. Now whenever the armature is attracted said conducting ring opens the circuit between springs 43 and 47, but closes its circuit between springs 42, 44, 45 and 46. It will also be 100 noted that a jumper 48 electrically connects springs 43 and 44. The general construction of the device will thus be apparent to those skilled in the art. By reason of the spring 31 a rather quick circuit change is 105 effected, thus securing a snap action movement.

Referring now more particularly to Fig. 6, which diagrammatically illustrates one form of the many circuit arrangements to 110 which my device is applicable, it will be seen that one terminal of the solenoid is connected to the spring 47 and the remaining terminal of the solenoids is connected to the right hand jack thimble 7. 115

Mains 49 and 50 of the current supply circuit are indicated. There is also shown a lamp 51 which is supposed to be in the nurses' quarters, lamp 52 which serves as the door lamp above the ward for instance 120 from which the call has come, and lamp 53 which is a bed lamp and directs the nurse to the particular bed from which the call has come. The lamps have one of their terminals all connected by way of the conductor 54 with the main 50. This same conductor 54 is also extended to connect with the left hand jack thimble 7. A conductor 55 connects the springs 43 and 44 with the main 49. Spring 42 is connected to the free 130

terminal of lamp 53. Spring 46 is connected to the free terminal of lamp 52 and spring 45 is connected with the free terminal of lamp 51.

Now whenever the plunger 32 is in the position shown in Fig. 4, then springs 43 and 47 are connected together. Thus if the push button is actuated at that time a circuit will be established which can be traced from the plunger portion of the push button 13 by way of conductor 56, plug 10, right hand jack thimble 7, solenoids 22, spring 47, conducting ring 35, spring 43, jumper 48, spring 44, conductor 55, main 15 49 to the source of power and back by way of main 50, conductor 54, left hand jack thimble 7, coöperating plug 10, and conductor 57 to the spring portion of the push button 13. Thus a circuit is established 20 for the solenoids 22 whereby they attract their armature 24 to thereby cause the plunger to assume its alternative position. The circuit through springs 47 and 43 is thereby broken and the solenoids are thereby deenergized. The armature 24 however 25 remains in its attracted position as there is nothing tending to restore it. With this new position of the plunger 32 circuit is established for all three of the lamps 51, 30 52 and 53, the circuit for one of the lamps for instance being traced from main 49, via conductor 55, spring 44, conducting ring 35, spring 42, conductor 58, lamp 53, conductor 54, to the main 50. Similarly the circuit for 35 the lamps 51 and 52 is simultaneously established.

As readily understood a great many of these switches can be used to operate individual lights, and in addition to operate pilot lights, for instance, the lamp 52 may be a pilot light for the ward corresponding to a great many switches at the different beds in the ward. It will thus be seen that my improved device is very flexible in that it permits of almost universal circuit interconnections for purposes such as these. The device is applicable to both A. C. and D. C. circuits.

Having thus described one embodiment of my invention, what I claim as new and desire to secure by Letters Patent is:

1. In a device of the character described the combination with a supporting plate, an electromagnet having a pair of coils projecting backwardly from said plate, a pivoted armature mounted backwardly of said electromagnet, one end of said armature overlying said electromagnet, a push button projecting through said plate and adapted 55 to coöperate with the end of said armature overlying said electromagnet, said push button being unconnected to said armature, a rod carried by the opposite extremity of said armature and having a lost motion connection therewith, a contact barrel carried 60 65

by said rod, a contact ring carried by said barrel, and long and short contact springs coöperating with said barrel, said springs by their frictional engagement with said barrel holding said barrel at either end of its throw, the springs of one length being adapted to control the circuit through said electromagnet and the springs of the other length being adapted to control signals.

2. In a device of the character described 70 the combination with a supporting plate, an electromagnet having a pair of coils projecting backwardly from said plate, a pivoted armature mounted backwardly of said electromagnet, one end of said armature overlying said electromagnet, a push button projecting through said plate and adapted to coöperate with the end of said armature overlying said electromagnet, said push button being unconnected to said armature, a 75 rod carried by the opposite extremity of said armature and having a lost motion connection therewith, said rod being slidably mounted in said plate, a contact barrel carried by said rod, a contact ring carried by said barrel, and long and short contact springs coöperating with said barrel, said springs by their frictional engagement with said barrel holding said barrel at either end of its throw, the springs of one length being adapted to control the circuit through said electromagnet and the springs of the other length being adapted to control signals.

3. In a device of the character described 80 the combination with a supporting plate, an electromagnet having a pair of coils projecting backwardly from said plate, a pivoted armature mounted backwardly of said electromagnet, one end of said armature overlying said electromagnet, a push button projecting through said plate and adapted to coöperate with the end of said armature overlying said electromagnet, said push button being unconnected to said armature, a 85 rod carried by the opposite extremity of said armature and having a lost motion connection therewith, a contact barrel carried by said rod, a contact ring carried by said barrel, long and short contact springs coöperating with said barrel, said springs by their frictional engagement with said barrel holding said barrel at either end of its throw, the springs of one length being adapted to control the circuit through said electromagnet and the springs of the other length being adapted to control signals.

3. In a device of the character described 90 the combination with a supporting plate, an electromagnet having a pair of coils projecting backwardly from said plate, a pivoted armature mounted backwardly of said electromagnet, one end of said armature overlying said electromagnet, a push button projecting through said plate and adapted to coöperate with the end of said armature overlying said electromagnet, said push button being unconnected to said armature, a 95 rod carried by the opposite extremity of said armature and having a lost motion connection therewith, a contact barrel carried by said rod, a contact ring carried by said barrel, long and short contact springs coöperating with said barrel, said springs by their frictional engagement with said barrel holding said barrel at either end of its throw, the springs of one length being adapted to control the circuit through said electromagnet and the springs of the other length being adapted to control signals.

4. In a device of the character described 100 the combination with a supporting plate, an electromagnet having a pair of coils projecting backwardly from said plate, a pivoted armature mounted backwardly of said 105 110 115 120 125 130

electromagnet, one end of said armature overlying said electromagnet, a push button projecting through said plate and adapted to coöperate with the end of said armature overlying said electromagnet, said push button being unconnected to said armature, a rod carried by the opposite extremity of said armature and having a lost motion connection therewith, said rod being slidably mounted in said plate, a contact barrel carried by said rod, a contact ring carried by said barrel, long and short contact springs coöperating with said barrel, said springs by their frictional engagement with said barrel holding said barrel at either end of

its throw, the springs of one length being adapted to control the circuit through said electromagnet and the springs of the other length being adapted to control signals, and contact springs carried by said plate adapted to receive a plug whereby energization of said electromagnet may be effected.

In witness whereof, I hereunto subscribe my name this 11th day of March, A. D., 25 1915.

EDWARD F. HAMILL.
